UNITED STATES PATENT OFFICE

HARRY W. BUNDY, OF DETROIT, MICHIGAN, ASSIGNOR, BY MESNE ASSIGNMENTS, TO
BUNDY TUBING COMPANY, OF DETROIT, MICHIGAN, A CORPORATION OF MICHIGAN

TUBING

Application filed November 18, 1927. Serial No. 234,088.

This invention relates to tubing, and particularly a water heater coil.

Water heaters ordinarily employ a relatively heavy copper tube approximately .040 of an inch in thickness of the walls. This is necessary in order to permit the bending of the tube on the radius employed in the average water heater.

It is the object of my invention to provide 10 a tube which can be made of relatively thin stock, and which at the same time has a flexibility which will permit the tube to be bent on a relatively small radius. This will permit water heater tubes to be made of much 15 lighter stock, and results in considerable saving in copper or other metal.

In the drawings:

Fig. 1 shows a water heater employing my improved tubing.

20 Fig. 2 is a view partly in section, showing one form of the tube.

Fig. 3 is a similar view, showing a different form of the tube.

25 Figs. 4 to 7 inclusive are sections showing different forms that the interior tube may take.

30 a designates an interior tube which may be fashioned in any one of the several present day production methods, as, for instance, with a lock-seam b, shown in Fig. 5, the tube being rolled or drawn through dies in the form of a strip and made in continuous lengths of lock seam. In Fig. 6 the so-called Bundy tube is used, being a two-ply tube. Such a tube 35 is shown in my Patent No. 1,431,368 of October 10, 1922. Fig. 7 is a form of lap-seam tube, and Fig. 4 is a form of seamless, welded, or brazed tube. The point is that the interior tube is a piece of "longitudinally fashioned" tube,—that is, tube fashioned into shape while traveling longitudinally either by dies, rolls, rolls and dies, or by the piercing operation used in making seamless tube, and then drawing it down to size. Welded and 45 brazed tube is also "longitudinally fashioned."

On the outside of the inner tube, I wind a close helix, or what is sometimes called a spiral. This gives the interior tube, which is made of thin stock, say .010 to .015 inch, 50 great strength against bursting strains by

reason of interposing the lengthwise strength of the outer tube stock to expanding strains on the inner tube. The result is that the outer tube stock may also be relatively thin, from .010 to .015 of an inch. At the same time 55 the outside helix permits great flexibility in this thin tube in bending.

In Fig. 2 the outside helix is wound in abutting relation. In Fig. 3 the outside helix is wound with a slight overlap. The helix 60 may or may not be soldered or brazed to the under tube. It is possible to wind the helix on very tightly, so that it will cling and take a seat on the inner tube. This arrangement is of course more flexible than the helix that 65 is soldered or brazed in place.

It will be apparent that the tube may be of copper, brass, steel or any other suitable material.

What I claim is:

1. As a new article of manufacture, a coil 70 bent on a relatively small radius, comprising a thin walled longitudinally fashioned tube of non-corrodible metal covered by a thin strip of metal wound as a helix on said tube 75 with the edges of adjacent convolutions of the helix in substantially abutting relation.

2. As a new article of manufacture, a coil 80 comprising a longitudinally fashioned tube of copper stock approximating .010 to .015 of an inch in thickness covered by a strip of metal wound as a helix upon said tube approximating .010 to .015 of an inch in thickness with the edges of adjacent convolutions 85 in substantial abutting relation.

3. A tube for a water heater coil or the like, comprising an inner tubular body of relatively thin copper stock which has substantially sufficient strength to withstand the internal pressure to which it is to be subjected, but which would collapse if bent to form a coil, and an exterior reinforcing metal strip wound helically upon the inner tube which reinforces the inner tube and permits it to be bent without collapsing, adjacent 90 convolutions of the helically wound strip being in substantially abutting relation.

4. A composite tube for a water heater coil or similar device requiring the tube to be bent, comprising an inner tube of copper hav- 100

ing relatively thin walls which would collapse if bent as required, as compared to walls of a conventional single ply tube for such a coil or the like, which are thick enough to prevent such collapse, and an exterior tube formed by metal stock of ribbon form wound helically upon the inner tube with adjacent convolutions in substantial abutting relation which reinforces the inner tube and permits it to be bent without collapsing, the walls of the composite tube consisting of the combined inner and outer tube walls having a thickness which is less than the thickness of the walls of the above mentioned conventional single ply tube.

15 In testimony whereof I have affixed my signature.

HARRY W. BUNDY.
